E. P. PORTER AND G. W. HALLETT, OF WATERFORD, NEW YORK.

Letters Patent No. 63,295, dated March 26, 1867.

IMPROVEMENT IN DOOR-LOCKS.

The Schedule referred to in these Letters Patent and making part of the same.

TO ALL WHOM IT MAY CONCERN:

Be it known that we, E. P. PORTER and G. W. HALLETT, of Waterford, in the county of Saratoga, and State of New York, have invented a new and useful Improvement in Locks; and we do hereby declare that the following is a full, clear, and exact description thereof, which will enable others skilled in the art to make and use the same, reference being had to the accompanying drawings, forming part of this specification, in which—

Figure 1 is a plan view of the relative position of the locking devices, when the bolt is thrown out and locked.

Figure 2, a plan view of the relative position of the locking devices when the bolt is drawn in.

Figure 3, a longitudinal section, taken in the plane of the line $z z$, fig. 1; and

Figure 4, a side view of a key suitable for the lock shown in the drawings.

Similar letters of reference indicate like parts.

In the lock embraced in this invention, a series of spring-catches are so arranged with regard to the bolt of the lock that when the bolt is thrown out they will so interlock or engage with the same as to hold it in such position until, unfastening or releasing the said catches from the bolt by a suitable key, the bolt is then left free to be drawn in.

A, in the drawings, represents the casing of the lock, B the square bolt, arranged to move or slide in the lock-casing, through a hole in one end, C, of which it passes and projects. This bolt, B, at D is slotted in the direction of and for a portion of its length, by which slot it moves over and upon the fixed key-pin, or spindle E of the back plate G of the lock-casing. H H, a series of catches, each hung upon a fulcrum-pin or centre, I, of the lock-casing, two upon each side of the bolt, along and in the same direction with which they extend. These catches are all of a similar shape or form, which consists in rounding off their ends toward the fixed key-pin E in an outward direction therefrom, and in forming at their opposite ends a square-shaped shoulder, J, which shoulder pieces J of the two catches, toward the inner end of the bolt, fit over such end with the shoulder pieces of the other catches, engaged with the shoulders K, formed by the cross-piece L of the bolt, at or near the end plate of the casing, through a hole, in which the bolt plays or projects. For the two catches of the lock upon the same side of the bolt, a bent spring, M, is provided, that at its centre is fixed in position to the lock-casing, but at its ends is loose, bearing by them against the catches at or near their shoulder ends; the object of these bent springs M being to hold the catches against the bolt, and, when disengaged therefrom by any suitable means, to throw them back into connection with them. Each catch, H, upon its edge toward the bolt is provided with a similar tube-shaped arm, N, through which a pin or stud, O, is arranged to play, resting by one end against the face of the bolt, where, by means of a bent spring, P, in each instance, it is securely held. The bolt B, at two points along each of its sides corresponding to the position of the pins O in each case, is provided with notches, R, having their upper surfaces inclined from one end to the other, forming a shoulder, S, at one end. T T, pins or studs secured to back plate of lock-casing, which pins act as guards to two of the spring catches, and not only prevent their being tampered with by inserting any implement in the key-hole of the lock, but also serve to confuse a person, if unacquainted with the construction of the lock, in attempting to unlock it. U U U, guard pieces secured to bolt B, for a similar purpose to that explained for the pins or studs T. V, a lug on bolt, against which the end portion W of the key, as shown in fig. 4, is to act for moving or throwing the bolt in or out, as the case may be, of the casing A, when such key is brought to bear against it in the proper direction therefor. X, a spring-catch secured to lock-casing in suitable position to engage with the bolt of the lock, and hold it when thrown out, as well also as to be acted upon or depressed by the key, when pushed inward, and thus relieved from the bolt previous to its being moved or drawn in by the action of the key against the lug of the bolt.

Having thus in detail explained the construction and arrangement of the various parts composing the lock, we will now describe the manner in which they operate, and the lock, locked or unlocked: When the lock is to be locked the key is first inserted in the key-hole of its casing, and then turned around until it comes against the lug V of the bolt, as shown by red lines in fig. 2 of the drawings, when, turning the key in the same direction to that in which the bolt is to move, the bolt is thus thrown out and the lock locked, where, by the spring-catches H, which, through their shoulders J, interlock with the bolt, as has been hereinbefore particularly

explained, and the catch X, it is held and secured, and in such a manner that it cannot be forced or drawn inward until such catches are released therefrom. In unlocking the lock the several catches, H, are released from the bolt by properly bringing the key to bear against them, to turn them on their fulcrum-pins I, where, held by the pins O in the ways R of the bolt, they are held, when, bringing the key against the lug V of the bolt, as shown in fig. 1, and then pressing it inwards sufficiently to release the catch X from the bolt, by then turning the key in the direction in which the bolt is to move, the bolt will be thus drawn into the lock-casing, as is obvious without any further explanation. What we claim as new, and desire to secure by Letters Patent, is—

1. The spring-catches H, whether more or less in number, in combination with the bolt B, when arranged together, substantially as and for the purpose described.

2. The catch X, in combination with the bolt B, substantially as and for the purpose specified.
